UNITED STATES PATENT OFFICE.

CHARLES S. BURTON, OF OAK PARK, ILLINOIS.

EXTENSION-TABLE LOCK.

1,130,141.

Specification of Letters Patent.

Patented Mar. 2, 1915.

Application filed November 17, 1913. Serial No. 801,340.

To all whom it may concern:

Be it known that I, CHARLES S. BURTON, a citizen of the United States, residing at Oak Park, in the county of Cook and State 5 of Illinois, have invented new and useful Improvements in Extension-Table Locks, of which the following is a specification, reference being had to the accompanying drawings, forming a part thereof.

10 The purpose of this invention is to provide an improved device for locking an extension table, and having adaptation especially for locking the parts of the table together when extended with fillers or leaves 15 interposed in the top, and in this respect adapted for so locking together the two members of a divided pedestal or supporting base when such members are spread apart for the purpose of extending the table 20 to admit leaves or fillers in the top.

It consists in the elements and features of construction shown and described as indicated in the claims.

In the drawings:—Figure 1 is a vertical 25 longitudinal section of an extension table embodying this invention, the same being shown at closed position of both top and pedestal. Fig. 2 is a similar view of the same with the top extended on the pedestal 30 and the pedestal halves extended, the locking devices being shown in locked position. Fig. 3 is a detail view showing the locking devices released for extending or closing up. Fig. 4 is a partly sectional detail side 35 elevation of the devices for connecting and drawing together the table halves. Fig. 5 is a section at the line 5—5 on Fig. 2 showing bottom end struts or braces for the pedestal halves. Fig. 6 is a detail elevation 40 of struts or braces for the lower end of the pedestal. Fig. 7 is a section at the line 7—7 on Fig. 6.

The table to which this invention is shown applied is shown in the common form of 45 pedestal table, having two pedestal halves, 1 and 2, adapted to be separated for extension, and having the corresponding halves, 3 and 4, of the top member mounted for movement upon the respective pedestal 50 halves for extension with or without opening or spreading the pedestal. The usual slides, 5, are shown for connecting the pedestal members with each other and the top member halves with the respective 55 pedestal members. The means of connect-

ing and drawing together the two halves of the pedestal comprise a toothed wheel, 6, which is journaled upon an upstanding lever, 7, fulcrumed at the foot of one pedestal member within the same; a rack, 8, 60 curved about the fulcrum of the lever mounted on said pedestal member for engagement of the toothed wheel; a chain, 9, having one end connected at 10 to the opposite pedestal half and extending over the 65 toothed wheel and down between the same and the pedestal wall forming a loop below the rack, 8, the end of the chain being connected at 11 to the bracket on which the rack is formed, and a flanged roller, 13, 70 which hangs in the loop of the chain below the bracket operating as a weight to take up the slack and retract the chain. The toothed wheel, 6, has its gear teeth, 15, engaging the rack at the lower side, and one 75 tooth, 16, at the upper side for engagement of the chain. The lever, 7, extends to the top of the pedestal and is there connected with means for operating it, as will be hereinafter explained.

80 The operation of the parts thus far described is as follows:—When the pedestal members are advanced toward each other in closing up, the weight, 13, hanging in the loop of the chain retracts it, holding it taut 85 from its connection at 10 with one pedestal member to and over the toothed wheel, 6, and in the absence of any engagement of the lever, 7, at the upper end, tending to hold the lever at its most inward position,—that 90 is, leaning toward the vertical axis of the pedestal,—the axle, 17, of the gear wheel being stopped by the upwardly projecting arm, 19, of the bracket, 8. Assuming that at this position, the pedestal members are not 95 entirely closed or clamped together, it will be seen that if the lever, 7, is pulled outward at the upper end, the teeth, 15, of the wheel, 6, engaging the rack, causing the wheel to roll on the rack as it is carried outward with 100 the lever, will cause the tooth, 16, engaged with the chain to be moved outward,—that is, toward the wall of the pedestal, 1,—twice as far as the axle of the gear is moved, and will thereby cause the pedestal halves to be 105 drawn toward each other twice as far as the movement of the lever at the point at which the wheel is journaled in it, thus drawing the pedestal halves together or clamping them firmly, taking up all the slack, if any, 110

in the chain, and closing up any crevice between the abutting edges of the pedestal members. If means are provided for not only moving the lever as described, but also for securing it at the point to which it is thus moved, the pedestal members will be firmly secured in clamped and locked relation to each other. Any customary means such as has been heretofore used in operating pedestal locks may be employed for thus operating and securing the lever, and such means will be entirely sufficient for all purposes if the halves of the top member are mounted fast on their respective pedestal members. But in a table of the type shown, in which not only the pedestal halves are separable for extension, but also the halves of the top member are movable upon their respective pedestal members for extension independently of the separation or spreading of the pedestal members, it is desirable to provide a means for operating and securing the lever which shall serve at the same time to close together the halves of the top member and secure them at the same time that the pedestal members are secured in locked position. For this purpose, lever-operating devices are provided which will now be described.

A draw bar, 25, lodged and extending horizontally at the top of the pedestal under the table top, has apertures, 25^a, 25^b, 25^c, each adapted for engaging the upper end of the lever, 7, and spaced apart in the length of the draw bar by distances equal to half of the unit-filler width, so that said draw bar moving with one of the top-member halves may have the said apertures engaged with said lever successively at closed position and at the positions to which the said top-member half will be moved for the insertion of one and two fillers, respectively, assuming that the other top-member half is equally moved in the opposite direction, as it should be to keep the table balanced. The draw bar, 25, has a slot, 25^d, by which it is slidably pivoted on a fulcrum, 26, carried by the top-member half, 3. A short link, 27, is also pivoted at one end upon the under side of said top-member half, and a handle lever, 28, is pivoted intermediate its ends to the free end of the link, 27, and at its inner end to the downwardly-bent end, 25^e, of the draw bar, 25, said draw bar having its said end bent downward at the outer end of the slot, 25^d. The locked position of the parts is shown in Figs. 1 and 2, the draw bar at that position having one of its apertures, as 25^a, engaged with the upper end of the lever, 7, the fulcrum, 26, being at the inner end of the slot, 25^d, the link, 27, being swung up about its fulcrum to a position at which the line from the pivotal connection of the said handle lever, 28, to the downwardly-bent end, 25^e, of the draw bar to the pivotal connection of

said handle lever to the free end of the link, 27, extends just above the fulcrum of said link, 27; and at this position the handle end of the handle lever is stopped against upward movement by a bumper, 30, on the under side of the table-top half, 3. At this position, the lever, 7, is at the extreme outward limit of its swing,—that is, leaned toward the outer wall of the pedestal member, 1,—and the maximum drawing and clamping action of the device is obtained and the table members are thereby presumed to be drawn and clamped together. If the operator now seizing the handle, 29, of the handle lever, 28, swings that lever downward and inward, its movement being controlled by the swing of the short link, 27, and the sliding of the draw bar on its pivot, 26, to the position shown in Fig. 3, the draw bar will be first thrust inward until the pivot, 26, stands at the outer end of the slot, 25^d, carrying the upper end of the lever, 7, inward, relaxing the clamping and slackening the chain, 9, between the wheel, 6, and the end securing, 10, of the chain, and leaving the engagement of the draw bar with the upper end of the lever, 7, loose. Upon the operator continuing the inward swinging movement of the handle past the point shown in Fig. 3, the pivot of the said handle lever to the link, 27, will be carried upward from the position shown in Fig. 3 until it passes the line from the fulcrum of the lever, 27, to the pivotal connection of the lever, 28, with the downwardly-bent end, 25^e, of the draw bar. In this movement, the draw bar being no longer able to slide longitudinally because the pivot, 26, is at the end of the slot, 25^d, operates as a bell-crank lever and is rocked over said pivot, 26, as a fulcrum, causing the inner end to be lifted clear of the upper end of the lever, 7, and when the pivot, 26, passes the said line from the fulcrum of the link, 27, to the pivot, 26, the handle lever being stopped against further upward movement by the fulcrum of the link, 27, the weight of the draw bar, 25, operating over its fulcrum, 26, causes the parts to be locked at that position. The operator may now extend the table to any degree permitted by its construction, the top members being free to slide upon the pedestal halves and the pedestal halves being free to spread, the chain, 9, sliding freely over the wheel, 6, because in the inward swing of the lever, 7, and the rolling of the wheel on the rack, the tooth, 16, which has engaged the chain passes out of engagement therewith, as seen in Fig. 4. The table being extended either as to top, or as to pedestal, or as to both, and the desired number of fillers being interposed between the top-member halves, the operator seizing the handle, 28, and swinging it downward and outward will first cause the draw bar to swing down toward the end of the lever, 7, and one

of its apertures, according to the number of fillers for which the top-member half has been extended, will become engaged with the end of the lever, this engagement occurring in the initial movement of the hand lever which carries the parts from the position shown in Fig. 1 to the dotted-line position shown in Fig. 3. The operator now continuing the outward swing of the handle will cause the parts to be drawn together. Probably usually the top members will come together first, because they will slide upon the pedestal halves more easily than the pedestal halves will move upon the floor. As soon as they come together, the further drawing action of the device causing the lever, 7, to be swung outward will cause the toothed wheel, 6, to pick up its engagement with the chain as the tooth, 16, moves upward toward the latter to draw upon the chain and close up the pedestal members, the parts at the close of the upward and outward swinging movement of the hand lever coming to locking position shown in full line in Figs. 1 and 2. It will be understood that upon opening up the top for extension, the top-member half, 4, will be moved outward as many times a half-filler-width distance as the number of fillers which it is desired to accommodate by the spreading of the top on the pedestal. Any familiar and convenient device may be employed for limiting the extension of this top half at the proper position to receive one or two or any other desired number of fillers, according to the amount of extension for which the top is constructed. A simple hook, 30, pivoted to the under side of the top member and adapted to be engaged with any one of the abutments, 31, 32 or 33, positioned at half-filler-width distances apart upon the top of the pedestal member, 2, will accomplish the proposition, the innermost abutment, 31, being positioned for securing the top-member half, 4, at closed position, and the abutments, 32 and 33, for securing it at position for admitting one and two fillers, respectively.

Ordinarily, each pedestal half is slightly overbalanced inward by the weight which it carries so that the pedestal members tend to spread apart at the bottom. When, however, the top members are extended to the maximum limit for which provision is made and the table is loaded, the excess of weight upon each pedestal half may sometimes be at a point outside the vertical line of its support upon the floor so that it may be overbalanced outward, which causes a tendency to close together the pedestal at the bottom rather than at the top. When this is the case, the operation of the clamping and locking devices described upon the pedestal, spread apart with fillers interposed in the top, is liable to cause the pedestal members to experience an excess of the draw-

ing action, whereby the pedestal members will be crowded toward each other at the bottom and the top will tend to bulge upward at the middle. This is preventable by providing struts to determine positively the limit of approach of the pedestal members at the bottom at the various stages of extension,—that is, for the admission of one or more fillers. For this purpose, I provide several struts or braces, 40, 41 and 42, of different lengths, which are all mounted upon one pivot at the foot of one of the pedestal members, and which when not in service lean back against the wall of that member, as shown in Fig. 1. The shortest strut is adapted to span the interval between the two pedestal halves at the bottom and abut endwise against the stop, 43, upon the other pedestal half when the two pedestal halves are spread for admission of one filler. The next longer strut, 41, is adapted to abut against the stop, 43, when the pedestal halves are spread to the extent of two filler widths, and the longest of the three is adapted to be swung to a similar position when the pedestal halves are spread three filler widths. Any additional number of longer struts may be provided, up to the limit of the height which can be accommodated in the pedestal at the position of the struts shown in Fig. 1. The operator upon opening the table will turn down to operative position the proper strut, according to the number of fillers for which the pedestal is spread.

I claim:—

1. In an extension table, in combination with the two separable members of the table and means by which they are connected for extension: a toothed wheel and a carrier for the same mounted on one member; a rack on the same member with which the toothed wheel engages; a chain attached to the opposite member and extending over the toothed wheel at the opposite side thereof from the rack, and means for moving the carrier to carry the wheel toward and from the opposite member.

2. In an extension table, in combination with the two separable members of the table and means which connect them for extension, a toothed wheel and a carrier for the same mounted on one table member; a rack mounted on the same member with which the wheel engages; a chain attached to the opposite table member and extending over the wheel at the side thereof opposite the rack, a weight carried by the chain beyond the wheel for taking up the slack of the chain; means for moving the carrier toward and from the opposite member, and means for locking the carrier at a position remote from the opposite member.

3. In an extension table, in combination with two supporting members and means

which connect them for extension; an up-standing lever fulcrumed at the lower end of one of said members; a toothed wheel carried by said lever at an intermediate position in the height of said member; a rack mounted on the same member, and engaging the toothed wheel; a chain connected to the opposite member and extending about the wheel at the opposite side thereof from the rack, the wheel having a tooth at that side for engaging the chain, the lever being extended to the top of said member, and means mounted under the table top for locking the lever at a position withdrawn from the opposite member.

4. In an extension table, in combination with two supporting members and means which connect them for extension; an up-standing lever fulcrumed at the lower part of one of said members; a toothed wheel carried by said lever; a rack mounted on the same member, and engaging the wheel; a chain connected to the opposite member and extending over the wheel at the opposite side thereof from the rack, the wheel having a tooth for engaging the chain at that side, the other end of the chain being connected to the first-mentioned member at an elevated point therein and drooping in a loop between the wheel and said connection, a weight carried by the loop to take up the slack of the chain, the lever being movable toward and from the opposite member, and means for locking it at withdrawn position.

5. In an extension table having two supporting members and means which connect them for extension; an upstanding lever fulcrumed on one member at the lower part thereof; a toothed wheel carried by the lever at an intermediate point in the height of said member; a rack mounted on the same member with which the toothed wheel engages; a guide track for the axle of the wheel in its movement with the lever toward and from the opposite member; a chain attached to said opposite member and extending over the wheel at the side thereof opposite the rack, the wheel being toothed for engagement of the chain over an arc adapted to be rolled out of such engagement by the movement of the lever rolling the wheel along the rack in engagement therewith; means for taking up the slack of the chain beyond the wheel, and means for locking the lever at a point in its movement remote from said opposite member.

6. In an extension table, in combination with two supporting members relatively movable for extension, and a top member movable for extension on one of the supporting members; a toothed wheel and a carrier therefor mounted upon one supporting member; a rack mounted on the same member engaging the wheel; a chain connected to the opposite member and extending about the

wheel opposite the rack; means for taking up the slack of the chain, and means mounted on said top member for engaging the carrier movable to withdraw the wheel from the opposite member, and means for locking 70 said carrier-operating means for holding the wheel at withdrawn position.

7. In an extension table, in combination with two supporting members connected for extension; a top member movable for extension on one of the supporting members; means which connect the two supporting members, adapted to permit their extension without disengaging such connection; means mounted upon one of said members for operating upon the connecting means to withdraw the two members toward each other; a device mounted upon said top member; a connection therefrom to said operating means adapted to be engaged therewith at a plurality of points along the length of said connection half-filler-width distances apart, said device being mounted movably on the top member to actuate said connection for withdrawing said operating means from the opposite member, and means for locking said device to hold it at such withdrawn position.

8. In an extension table, in combination with two supporting members and a top member movable upon one of them, and means which connect said three parts for extension; devices for connecting and drawing together the two supporting members, comprising an operating member whose upper end is engageable for its operation; a device mounted upon said top member for so engaging and operating it, said device comprising two fulcrum supports on the under side of said top member; a draw bar mounted for sliding on one of said fulcrums having means for engaging said operating member positioned at a plurality of points along the length of the draw bar half-filler-width distances apart; a link mounted upon the other fulcrum; an operating handle 110 pivoted to the free end of said link and to the draw bar at a point on the latter offset from the line of sliding near the outer limit of the slideway of said draw bar, whereby the draw bar is lifted at its inner 115 end upon continuation of a movement causing it to slide to that limit.

9. In an extension table, in combination with two supporting members and a top member movable upon one of them, and means which connect said three parts for extension; devices for connecting and drawing together the two supporting members, comprising an operating member whose upper end is engageable for its operation; a device mounted upon said top member for so engaging and operating it, said device comprising two fulcrum supports on the under side of said top member; a draw bar having a slideway for sliding on one of said 130

- fulcrums having means for engaging said operating member positioned at a plurality of points along the length of the draw bar half-filler-width distances apart; a link 5 mounted upon the other fulcrum; an operating handle member pivoted to the free end of said link and to the draw bar at a point on the latter offset from the line of sliding near the outer limit of the slideway of said 10 draw bar, the pivot of said link to the handle member being distant from the pivotal connection of the handle member to the draw bar more than the length of said link, the relative positions of the two fulcrums 15 and the two pivots of the handle member being such as to permit the pivot of the link to the handle member to be moved by the swinging of the link past the line connecting the second fulcrum with the other pivot 20 of the handle member, and means for stopping the handle member in each direction.
10. In an extension table, in combination with two supporting members; a top member movable on one of them and means 25 which connect said three parts for extension; devices for connecting the two supporting members; means for operating said devices to draw the supporting members together; means connecting said operating 30 means with said top member, and means for operating the last mentioned connections to move the top member relatively to said operating means, and a plurality of struts or braces of different lengths pivoted upon one 35 supporting member near the bottom, and adapted to be folded up into said member, and to be folded down into approximately horizontal position to stop the approach of the opposite member, each of the shorter of
- said struts or braces being adapted to be so 40 folded down without a longer one.
11. In an extension table, in combination with the two supporting members adapted to be spread apart for extension of the table; means for connecting said members 45 at extended position and for drawing them toward each other to clamp interposed fillers in the top; struts or braces hinged to one of said supporting members near the lower end, adapted to be folded down transversely of the parting plane of the two members to stop the approach of the members when drawn together.
12. In an extension table, in combination with the two separable members of the 50 table and means connecting them for extension; a lever pivoted near the foot of one table member; an element pivoted intermediate its ends to the said lever intermediate the ends of the latter; a part fixed on the 55 same table member engaged with the lower end of said pivoted element; a flexible connecting element attached to the opposite table member and engaged with the upper end of said last mentioned pivoted element, 60 and extending thereover and down at the opposite side thereof; and means for moving the first mentioned lever to carry the pivot thereto of said pivoted element toward 65 and from the opposite table member.

In testimony whereof, I have hereunto set my hand at Chicago, Illinois, this 13th day of November, 1913.

CHARLES S. BURTON.
